UNITED STATES PATENT OFFICE.

CARL AUGUST MÜLLER, OF WITZENHAUSEN, GERMANY.

SAFETY-LOCK.

973,455.

Specification of Letters Patent. Patented Oct. 18, 1910.

Application filed September 6, 1907. Serial No. 391,672. (Model.)

To all whom it may concern:

Be it known that I, CARL AUGUST MÜLLER, lock manufacturer, a subject of the German Emperor, and resident of Witzenhausen, 5 Germany, have invented an Improved Safety-Lock, of which the following is a specification.

The object of the present invention is a safety lock in which a key, which can be 10 conveniently placed in a purse, pocket or the like, is used to couple the handle with the roll back and to unlock the handle. This key is made to correspond with a number of tumblers arranged in the lock, which prevent the handle from being connected to the 15 roll-back. After the lock has been locked or unlocked, the key is withdrawn. In the key is an aperture which corresponds to a projection on the roll-back of the lock. 20 When the key has been pushed down far enough into the lock, the aperture fits over the projection, and the lock can be unlocked by turning the handle. To prevent such a lock being unlocked by pins, there are 25 grooves in the cylindrical part of the handle casing in which the pins would catch when the handle is being turned. To prevent the key catching in these grooves it is either provided with noses or is wider than the 30 grooves.

In order that the present invention may be more clearly understood, reference is made to the annexed drawing.

Figure 1 and Fig. 2 show sections on 35 A. A. Fig. 3. Fig. 3 is a front view of the lock. Fig. 4 is an outside view of the lock. Fig. 5 is a section on B. B. Fig. 1. Fig. 6 shows two views of the key.

The bolt *a* is moved in the known manner by means of the projections *c* on the roll-back *b*. The roll-back *b* can be turned from outside by the handle *d*, when this latter has been pushed sufficiently into the lock *e*, after a key *f* with an aperture *h*, has been 40 inserted in the cylindrical part *g* of the handle *d*, and pushed down by means of a slider *e*, so that the aperture *h* in the said key *f*, coincides with a projection *i* on the shaft of the roll-back *f*. In order that the 45 projection *i* of the roll-back *b* will always coincide with the aperture *h* in the key, both, when the lock is unlocked and locked, a stop shoulder *k* is provided on the lock casing for the projections *c* of the roll-back *b* so that the movement of this said roll-back *b* is limited.

Although the aperture *h* in the key *f* with a corresponding projection *i* on the roll-back *b*, which can be of various forms and shapes and sizes, affords a great security 60 against unauthorized operation of the lock, this security can be further increased by the form of the tumbler *l* with which the key *f* must correspond. These tumblers generally keep the handle locked against movement, 65 *i. e.* they prevent the handle from forming the necessary coupling, with the projections on the roll-back *b*, as they are pressed by springs *m* into a groove *n* in the casing *o* around the cylindrical part *g*, Fig. 1. Only 70 when the correct key *f* is inserted can the tumblers *l* of which there may be any number, and whose width corresponds to a cut in the key *f*, as shown by dotted lines in Fig. 5; be pressed out of the groove *n*. The handle *d* together with the tumblers *l* and the key *f*, can then be pushed into the lock until the aperture *h* in the key *f* is passed over the projection *i* on the roll-back *b*. To further 75 prevent the unlocking of the lock, there is a counter groove *p* in the casing *o* into which the tumblers may be pressed when a false key is being used, so that the handle cannot be pushed into the lock.

In order that when unlocking or locking the lock, to ascertain if the handle is in the correct position opposite the slider *e* so as to allow the key *f* to be inserted, there is a spring influenced pin *q* in the casing *o* which projects into a hollow in the handle (Fig. 1,) but is released from the handle when this latter is pushed into the lock (Fig. 2). To prevent the handle *d* and the cylindrical part *g* from being pulled back when they are turned, noses *g²* on the cylindrical part *g*, 90 pass through cuttings in a circular groove *g¹* in which the said noses turn when key *f* is pressed into engagement with the roll-back spindle.

The slider after pressing in the key *f*, is 95 held in a fixed position by means of a spring influenced pin *r*. After the lock has been locked, the key *f* is turned by means of the handle *d*, and cylindrical part *g*, and when these latter are pulled out, the said key *f* falls into a tray *t* arranged at the bottom 100 of the casing *o* and from where the key *f* can be taken out.

To prevent the insertion of a false key *f*, 110 this latter possesses a groove *u*, so that it can pass a pin *v* in the inserting channel. To obviate the lock shield being unscrewed, two

screws w are passed through the face plate z and screwed into nuts held to the outer locking shields by means of clamp cheeks y .

- The locking of the above described lock is effected in the following manner:—The key f is inserted in the insertion channel and pushed down by the slider e . The handle is then released from the tumblers l which are pushed out of their groove n by the key.
- 10 The handle together with the tumblers and the key is then pushed into the lock and turned in the direction of the arrows, Fig. 4, the projections g^2 then turning in the grooves g^1 . After the handle has been 15 turned, it is pulled back together with the parts g , l , f when the key falls into the tray t , which latter can be pulled into the dotted position shown in Fig. 1 so that the said key can be taken out.
- 20 Having now fully described my invention, what I claim and desire to secure by Letters Patent is:—

An improved safety lock, *i. e.* a casing, a roll back situated therein, projections on said 25 roll back, a stop shoulder to limit the move-

ment of said projections, a projection (t) on the end of the roll-back, a handle a key serving to couple the handle to said roll-back, a cylindrical casing with a slot on top for the insertion of the key, tumblers in said casing, 30 a slide adapted to force the key into engagement with the tumblers, a spring controlled pin for holding said slide in position, a cylindrical part carried by the handle, noses on said cylindrical part, said noses being 35 adapted to pass through openings in a groove in said cylindrical casing when the handle is pushed in, and a spring controlled pin carried by said cylindrical casing and adapted to engage in a recess in said cylindrical part, substantially as described and shown.

In testimony whereof I have hereunto set my hand in the presence of two subscribing witnesses.

CARL AUGUST MÜLLER.
